Inventor.

Loren J. Wicks

UNITED STATES PATENT OFFICE.

L. J. WICKS, OF RACINE, WISCONSIN, ASSIGNOR TO HIMSELF AND THOMAS BURBECK, OF SAME PLACE.

BOOT-JACK.

Specification of Letters Patent No. 22,923, dated February 8, 1859.

To all whom it may concern:

Be it known that I, L. J. Wicks, of Racine, in the county of Racine and State of Wisconsin, have invented certain new and useful Improvements in Boot-Jacks; and I do hereby declare that the following is a full, clear, and exact description thereof, reference being had to the accompanying drawings and to the letters of reference marked thereon.

10 The nature of my invention consists in constructing boot jacks substantially in the manner hereinafter described.

15 In the annexed drawings Figure 1 is a perspective view of the jack ready for use, as such. Fig. 2 is a plan view showing the several parts in different positions. Fig. 3 is an edge view showing the parts folded together.

20 In the figures A, B, and C, represent three arms—A, and B, being the main arms, which are supported when used for a boot jack by the arm C. The arms A, and B, are pivoted together at d, in such a manner as to allow 25 them to play freely like a pair of scissors.

a, represents a pin secured to the arm A, against which the rear of arm B, strikes when said arms are separated for use as a boot jack.

30 The arm A is provided at its heel with a hammer which consists of the head D, and claws E, the front end of this arm being so constructed as to form a screw driver. Arm B, is provided at its rear with a cork screw F, its forward end being turned up as shown in the drawings forms a shield and protection for the point of the screw driver.

35 Arm C, is pivoted to arm B, at e, and is in two parts which are connected together by a hinge at x. This hinge allows the front end 40 of arm C, to turn down in the manner shown

in Fig. 1 and thus forms a support for the arms A, and B, when in use for a boot jack.

It is not necessary that the arm C, should be pivoted at e, on arm B, thus taking two pivots to connect the parts. It may be secured by the pivot d, thus making all of the arms to turn upon one and the same pivot.

45 The uses to which this jack may be put are several.

When in the form shown in Fig. 1, the boots may be readily removed from the feet by means of it.

50 When in the form shown in Fig. 2, the scraper G, may be used for taking the sealing wax from bottles or for other similar purposes—the cork screw F, may be used for removing corks from bottles, and the screw driver H, is in position to be used for removing screws, the hammer forming a handle 55 for said screw driver.

55 When in the form shown in Fig. 3 the implement may be used as a hammer for driving tacks or nails, or for drawing them as circumstances may require.

60 It will here be seen that economy can be displayed in the formation of a boot jack, the ends of the arms forming the same, subserving varied and useful purposes.

65 Having thus fully described my invention 70 what I claim as new and desire to secure by Letters Patent is—

The within described boot jack as an article of manufacture, with the tools formed on the rear or front of its arms, said arms being 75 made to open, or shut together, substantially in the manner specified.

LOREN J. WICKS.
